UNITED STATES PATENT OFFICE

MAX MEYERSON, OF NEW YORK, N. Y.

CONTAINER

Application filed March 17, 1927. Serial No. 175,986.

This invention relates to a container, and an object of the present invention is to provide a container which may be formed principally of sheet fibre board, ordinary cardboard or other appropriately light and strong sheet material, the container being so designed and re-inforced that it will be strong and substantial notwithstanding the lightness of the material from which it is constructed.

10 A further object is to so design the container that it may be well adapted to the storing and transportation of delicate materials such as expensive silks and the like, and to this end an essential object is to make the interior of the container wholly devoid of the presence of rivet heads or other protruding parts which are likely to snag the contents and cause injury thereto.

15 A further object is to so construct the container that it may be quickly, easily and cheaply manufactured, relatively large containers requiring only relatively small pieces of fibre board or the like in its make-up.

20 A more detailed object is to provide a container of the type indicated and in which the joints between adjacent pieces of fibre board are formed partly by laterally turned portions of the fibre board and partly by a metallic strip clamping said laterally turned portions together and serving therewith to greatly re-inforce the mechanical strength of the joints.

25 Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claim.

30 In the accompanying drawings which are to be taken as a part of this specification, and in which I have shown merely a preferred form of embodiment of the invention:-

35 Fig. 1 is a side elevational view, partly in vertical section, of a container constructed in accordance with this invention and including a cover member therefor.

Fig. 2 is an enlarged fragmentary detail sectional view taken substantially upon the plane of line II—II of Fig. 1.

Fig. 3 is a fragmentary top plan view of a portion of the cover member.

Fig. 4 is a bottom plan view of the parts seen in Fig. 3.

Fig. 5 is a fragmentary detail sectional view showing the manner in which the bottom wall of the container may be connected with the side wall, and

Fig. 6 is a bottom plan view of the structure seen in Fig. 1, the view being on a greatly reduced scale, for economy of space.

Referring to the drawings for describing in detail the structure which is illustrated therein, and bearing in mind always the fact that the structure as shown and described is given merely as an example of one embodiment of the invention, the container will be referred to generally as comprising a side wall or walls L, a bottom wall G, and a top or cover wall or member H.

The container may be constructed of any shape or size desired, but for convenience of illustration it is shown as being cylindrical.

The side walls L are made up of a series of separate pieces or sheets as 1—1. These may be of thin sheet fibre board, cardboard, or other suitable material. They are each of a height to extend preferably from the top to the bottom of the container, but they may be of any desired width so that any number thereof, according to their width, and the size of the container, may complete the entire side wall structure. Each of these side wall pieces has its opposite vertical edge portions turned laterally outwardly to provide vertical flanges as 2—2 thereon, the flanges of adjacent pieces being made to stand flat against each other so that collectively they define a very substantial rib vertically of the side wall structure, there being of course one such rib between each two side wall pieces.

In order to hold the flanges 2 together, and thus unite the side wall members, suitable clamp strips 3—3 are provided, one for each pair of flanges. These strips are of U-shape in cross section and have their opposite leg portions engaging over the outer surfaces of 109

the flanges, the size being such that the legs tightly grip the flanges between them. The clamp strips are preferably formed of sheet metal and in some instances they may be operated upon to bend their opposite legs into a more tight engagement with the confined flanges after they have been slipped over said flanges, and if desired, an even greater measure of security may be afforded by passing 10 rivets or the like as 4 through the clamp strips and through the interposed flanges in order to hold the clamp strips more positively and firmly in position.

It is noted that the clamp strips, the flanges 15 engaged thereby, and even the rivets or other retaining means 4 which go to make up the joint between adjacent side wall pieces are wholly and entirely on the outside of the container, the inside surface being maintained 20 smooth and free of objectionable obstructions of any kind.

Obviously the metallic clamp strips 3 serve the added purpose of greatly re-inforcing the rib formed by the flanges 2-2, so that the 25 complete joint structure is of great strength not only as a joint for firmly connecting the adjacent side wall pieces but also as a strengthening rib vertically of the container, it being noted that these metallic clamp strips extend 30 continuously between the upper and lower ends of the container.

A suitable binder strip 5 is arranged at the upper edge of the container, consisting preferably of a strip of sheet metal bent into U 35 cross section and fitting over the upper edge of the side wall pieces. The upper end portions as 6-6 of the clamp pieces 3 project upwardly beneath the outer leg of this binder strip and are thus held in a neat, strong and 40 compact relationship. The binder strip may be bent to provide pockets as indicated at 7 if desired in order to more firmly and neatly receive the upper end portions of the clamp strips.

45 To hold the binder strip connected with the upper edge portion of the wall pieces the opposite legs of said strip may be pressed together so as to clamp the wall pieces between them and thus frictionally prevent dislodgement of the binder strip, and in addition to this a series of punch depressions as at 8-8 may be formed in one or both legs of the binder strip to thereby more positively retain the binder strip.

50 A similar binder strip as 9 is arranged at the lower end of the container straddling the lower edge of the side wall members and having pockets as 10 at appropriate points there- 60 in to receive the lower end portions 11 of the clamp strips 3, and held by punch depressions or the like as 12, all in the same manner as described with respect to the binder strip 5.

The bottom wall G of the container may 65 consist of a single sheet of fibre board, card-

board, or other suitable material sufficiently large to close the entire lower end of the container, or if desired, as may be the case with large containers, the bottom wall may be made up of several separate pieces joined together by having edge portions of said pieces turned downwardly and held together by clamp strips in the same manner as above described with regard to the joints between the side wall members 1-1, one such joint being illustrated for example as at 13 in Fig. 6, in which instance of course the presence of the joint not only enables the use of relatively smaller pieces of wall-forming material but also greatly re-inforces the wall in withstanding the strains to which it is subjected particularly where the bottom wall is of great surface extent.

The bottom wall may be held in position connected with the lower marginal parts of the side wall pieces in any suitable manner. In Fig. 1 the bottom wall is shown as being provided with a marginal flange 14 turned downwardly thereon and resting against the inner surface of the side wall pieces, being held connected therewith by being received behind the inner leg 15 of the binder strip 9. This flange 14 may continue around the entire marginal portion of the bottom wall and the bottom wall be thus held fixed in position, or if desired said flange may be omitted at some points about the margin of the bottom wall, and the marginal edge of said bottom wall be at these points made to engage within recesses 16 provided for the purpose within the material of the side wall pieces, as illustrated in Fig. 5. Or the bottom wall may be connected with the side wall pieces by being extended into a recess 16 extending throughout the length of the side walls, in which instance the flange 14 might be entirely omitted.

In any event the inner leg 15 of the binder strip 9 is preferably provided with a horizontal extension 17 projecting beneath the adjacent marginal part of the bottom wall to thereby re-inforce said marginal part and assist in the efficient support of said bottom wall upon the side walls.

Where the bottom wall is formed with a cross seam or seams as 13 in Fig. 6 the clamp strip or strips comprised in said seam or seams, and bridging across the expanse of the bottom wall, will have the end portions thereof extended between the bottom surface of the bottom wall and the upper surface of the horizontal extension 17, as indicated in Fig. 6, so that said clamp strip or strips will be positively supported upon the metallic binder strip and be thereby rendered capable of adding increased support for the intermediate portions of the bottom wall.

There may be as many of the vertical reinforced joints in the side walls, and as many of the horizontal reinforced joints in the bot-

tom wall, as may be desired or as may be necessary to produce the required strength for a container of a given size or which is intended for a given purpose. Each added joint will 5 materially increase the strength of the entire structure and at the same time will always render possible the use of relatively smaller pieces of fibre board for a given size of container and thus reduce the cost of the fibre board and compensate in a measure for the added labor and material in the joint.

The cover H consists simply of a single piece of fibre board or the like as 18 of a suitable size to overlie the upper end of the 15 container. To increase its rigidity and serve in connecting it with the remainder of the container it is preferably furnished with a marginal metallic binder strip 19 of U-shape in cross section and straddling over the edge 20 of the fibre board 18 so that one flange as 20 of the strip rests upon the upper surface of the fibre board and the other flange as 21 engages the under-surface of the fibre board. The nether flange 21 may be formed with a 25 lateral extension part as 22 thereon arranged to telescope within the upper end of the container in a well-understood manner for retaining the cover frictionally in position upon the container in use.

As illustrated in Figs. 3 and 4 the strip of material comprising the binder strip 19 may have its opposite ends connected together by having one end thereof as 23 telescoped into the opposite end as 24 and said two ends be 35 held together and to the fibre board by means of a rivet or the like as 25 extending through all of said parts. In order that the end edge of the over-lapping part 24 may not present an objectionable corner for injury to 40 the hands, or to any material being placed into or taken out of the container, the underlying part 23 is preferably formed with a slide head as 26 thereon adjacent the end edge of the part 24 so as to partially conceal and 45 protect said edge.

The fibre board 18 of the cover, like the bottom wall G of the container, may be formed of more than one piece, in which event the several pieces will be connected together by re-inforcing seams in the same manner as already described with respect to the bottom wall, and the metallic re-inforcing clamp strip would have their ends engaged beneath the upper flange part 20 of the 55 binder strip 19 for greater rigidity etc. as already explained with regard to the joint 13, the seam being of course formed at the upper side of the cover so as to leave the under-side smooth and unobstructed.

It should be particularly noted that the 60 binder strips 5, 9 and 19 are each respectively formed from a single continuous strip of sheet material bent lengthwise around the margins of the parts which they engage, that is the 65 binder strip 5 is bent around the upper mar-

gin of the container, the binder strip 9 is bent around the lower margin, and the binder strip 19 is bent around the margin of the cover. The two ends of the material comprising each of these strips are connected together by a 70 joint which is the only joint throughout the length of the strip. The joint shown in Fig. 3 is simply an example of one type of joint which may be employed. This same type may be employed for connecting together the 75 ends of the strip of material comprising the binder strip 5 or for connecting together the ends of the strip of material comprising the binder strip 9, or any other form of joint may be employed. The abutting ends of the 80 strip may if desired be connected simply by being welded together in some instances.

As many changes could be made in this construction without departing from the scope of the invention, as defined in the following 85 claim, it is intended that all matter contained in the above description or shown in the accompanying drawings shall be interpreted as illustrative only and not in a limiting sense.

Having thus described my invention, what 90 I claim as new and desire to secure by Letters Patent is:—

A container comprising side walls and a bottom wall, said side walls being made up of a series of vertical panels of fibre board each 95 panel consisting of a separate sheet of fibre board, said sheets being arranged side by side to complete said side walls, each of said sheets having outwardly projecting flanges at their vertical edges said flanges of adjacent 100 sheets abutting flat against each other and extending from near the top to near the bottom of said sheets, a pair of metallic re-inforcing binding strips one at the top edge and the other at the bottom edge of the container each 105 of U cross section extending entirely around and fixedly straddling the respective edge so as to provide a continuous metallic bond between the several panels at said edge, the bottom wall comprising a piece of fibre board 110 engaging and being supported by the bottom edge re-inforcing strip, a plurality of metallic vertical re-inforcing strips spaced apart circumferentially exteriorly of the container each of U cross section throughout 115 its mid portion arranged so that the legs of the U stand in substantially right angular relation to the adjacent outer wall surface of the container, said legs of each strip serving as clamp members straddling and clamping one pair of the mentioned abutting flanges of the wall sheets, the upper and lower end portions of each vertical re-inforcing strip continuing beyond the ends of said flanges and 120 to approximately the upper and lower edges of said sheets and being flattened out to lie flat against the outer surface of said sheets, and the outer leg of the U of each of the top and bottom edge re-inforcing strips being 125 130

bent to definitely define a series of pockets between themselves and the underlying outer surface of the wall sheets arranged to receive and to fit to and retain the adjacent flattened ends respectively of the vertical re-inforcing strips.

In testimony whereof I affix my signature.

MAX MEYERSON.
